UNITED STATES PATENT OFFICE.

EDWARD F. McCOOL, OF VICTOR, COLORADO.

GRINDING-MILL.

1,137,224.

Specification of Letters Patent. Patented Apr. 27, 1915.

Application filed May 27, 1912. Serial No. 699,907.

To all whom it may concern:

- Be it known that I, EDWARD F. McCool, a citizen of the United States, residing at Victor, county of Teller and State of Colorado, have invented certain new and useful Improvements in Grinding-Mills; and I do declare the following to be a full, clear, and exact description of the invention, such as will enable others skilled in the art to which it appertains to make and use the same, reference being had to the accompanying drawings, and to the characters of reference marked thereon, which form a part of this specification.
- 15 My invention relates to improvements in grinding mills, my object being to provide an efficient construction of this class, in which provision is made for permitting a yielding movement in a longitudinal direction of the rotary member of the grinding head in order to prevent breakage or injury to the mechanism due to the entrance to the grinding jaws of a metal article or other foreign device which is too hard to be crushed. It sometimes happens that a metal tool, as a wrench, is accidentally fed, with the ore, rock or other material to be ground, into the space between the jaws or grinding members.
- 20 One of the objects of my present construction is to prevent injury to the machine due to an accident of this character. While provision is made for permitting the rotary member of the head to move away from its relatively stationary member under the circumstances described, I also provide means whereby a clutch carried by the rotary hollow shaft is disconnected from the operating pulley from which power is transmitted to the hollow shaft through the instrumentality of the said clutch. Hence, by virtue of my improved construction, when the rotary grinding member yields to prevent injury to the apparatus, the shaft which imparts movement to the grinding member is simultaneously disconnected from the power which drives the machine whereby the moving parts are quickly stopped.
- 25 Provision is further made for producing an air-current within the housing inclosing the grinding members, whereby the pulverized material, when reduced to the proper fineness, is removed from the housing, while particles which pass from between the grinding members into the housing and which are

not sufficiently fine for the purpose, will drop into a removable receptacle and may be introduced into the hopper for re-grinding. The air-current is made of such strength and so regulated as to remove only such particles as have been properly reduced.

Having briefly outlined my improved construction, I will proceed to describe the same in detail, reference being made to the accompanying drawing in which is illustrated an embodiment thereof.

In this drawing: Figure 1 is a longitudinal section taken through a grinding mill equipped with my improvements, parts, however, being shown in elevation. Fig. 2 is a detail view of the friction-clutch shown on a larger scale. Fig. 3 is a sectional view of the same. Fig. 4 is a detail view of the gearing whereby motion is transmitted from the hollow shaft to an interiorly-located and independently-movable operating shaft, the latter being eccentrically mounted in the hollow shaft and employed for imparting direct rotary movement to the movable member of the grinding head. This view is obtained by looking in the direction of arrow 4 Fig. 1. Fig. 5 is a section taken on the line 5—5 Fig. 1 looking toward the right or in the direction of the arrow adjacent said line. Fig. 6 is a side elevation of the rear extremity of the machine or a view looking in the direction of arrow 6 Fig. 5. Fig. 7 is a front end elevation of the machine or a view looking in the direction of arrow 7 Fig. 1. Fig. 8 is a side elevation of the forward extremity of the machine, showing the housing and the stationary jaw swung away from the movable jaw or grinding member. Fig. 9 is a side elevation of the same showing the parts in the closed position. Fig. 10 is a section taken on the line 10—10 Fig. 1 looking toward the left.

The same reference characters indicate the same parts in all the views.

Let the numeral 5 designate a suitable frame-work in which is journaled a hollow shaft 6 upon which is splined a friction-member 7 adapted to engage a power-pulley 8 which is connected with a motor or other suitable power not shown. As illustrated in the drawing, this clutch-member is composed of a hub 9 splined upon the hollow shaft by a key 10. Formed integral with this hub is an open web 12 having radially-disposed members 13 provided with

5 recesses 14 in which are located sleeves 15 which are quite loose within the recesses and pivotally connected with the members 13 by means of pivot-pins 16, the said pins being located near the inner extremities of the said sleeves to permit a slight rocking movement of the sleeves with their respective recesses. Applied to each member 13 forward of its sleeve 15 is a rigid screw 17 10 located near the outer extremity of the sleeve, which may be adjusted to regulate the swinging or tilting movement of the sleeve. On the opposite side of the sleeve and located directly across from the screw 17, is a spiral spring 18 which permits the sleeve to move or swing rearwardly on its pivot.

15 Threaded into the sleeve 15 is a screw 19 which is centrally provided with a part 20, 20 fashioned to receive a wrench for adjusting purposes. This screw is threaded at both extremities, its outer portion 21 being threaded into a similar sleeve 22 which is movably mounted on a pivot-pin 23 located 25 near its outer extremity, and threaded into the friction member 11 of the clutch which is movable independently of the body-member for releasing purposes. Applied to this friction member in the rear of the sleeve 22 is 30 a screw 24 which may be adjusted for limiting the movement of the sleeve and the screw 19. Opposite this screw 24 and located in a recess also formed in the friction member, is a spiral spring 25. The friction member which is connected with the sleeve 22 by the pivot-pin 23 as aforesaid, includes a shoe 26 composed of a metal member 27 and a member 28 preferably composed of wood and connected with 35 the metal member by a suitable fastening device 29. The inner portion of each friction member 11 is recessed to receive the sleeve 22 which is loosely arranged therein for the same purpose as the similar arrangement of the sleeve 15 in the recess 14 of the 40 body of the clutch.

45 By virtue of the construction and arrangement of the clutch, as heretofore described, it will be understood that by moving the 50 same slightly rearwardly on the hollow shaft 6, each screw 19 will be permitted to assume a position slightly inclined to the normal position. In other words, by a slight movement of the clutch member toward the left 55 (see Fig. 1) on the hollow shaft 6, the inner extremity of each of the screws 19 will be caused to swing slightly rearwardly, while its outer extremity will lag, whereby each screw 19 will be slightly tilted so that its 60 inner extremity shall be farther rearward than its outer extremity. This will result in moving each friction member 11 of the clutch slightly inwardly, whereby the clutch and consequently the shaft 6 is disconnected 65 from the power pulley.

The forward extremity of the hollow shaft 6 is equipped with a crank-arm 30 whose outer extremity is provided with a wrist-pin 31 on which a gear 32 is mounted to rotate. This gear travels in a relatively large exteriorly-located stationary gear 33 and meshes with a relatively small gear 34 keyed to the operating shaft 35 which is eccentrically mounted within the hollow shaft 6. In this manner rotary movement is imparted 70 to the operating shaft at a different speed 75 from that of the rotary shaft.

To the forward extremity of the operating shaft 35 is attached, as shown at 36, a hollow bracket 37, having a forwardly-located elongated opening 38 adapted to receive a rectangular member 39 formed on a rotary grinding member 40, the last named member being hollow, as shown at 41, to receive the face parts 42 of the hollow 80 bracket on opposite sides of the opening 38. The grinding member 40 is applied to the hollow bracket by inserting the rectangular rearwardly-located part 39 of the grinding member, into the opening 38 of the hollow 85 bracket and moving the same rearwardly against the forward extremity 43 of the operating shaft which is allowed to yield in the rearward direction sufficiently to bring the part 39 within the hollow or concavity 44 of the bracket in the rear of the face members 42 of the bracket, and also in the rear of lugs 45 which extend rearwardly and are separated to receive the part 39 of the grinding-head when the latter is given a 90 quarter-revolution after inserting the part 39 within the opening 38 of the bracket. As 95 soon as this is done, the part 39 (see Fig. 10) may move forwardly between the lugs 45, and as the operating shaft 35 is normally 100 thrust forwardly, as hereinafter explained, while the bracket is normally thrust rearwardly, the grinding-member 40 will be securely held in operative relation with the operating shaft.

110 The bracket 37 is normally thrust rearwardly on the operating shaft by a spiral spring 46 located within the hollow of the bracket and having its rearward extremity bearing against the rear end of the bracket 115 on the inside, while its forward extremity engages a stop disk 47 applied to the forward extremity of the shaft 35. The forward extremity of the shaft 35 is rounded, as shown at 48, and engages a recess 49 of 120 counterpart shape formed in the grinding member 40. The outer engaging parts of the bracket and the grinding-member are so constructed as to permit the grinding-member a slight rocking movement on the 125 bracket from a point 50 as a center. This movement will facilitate the grinding action of the apparatus.

130 The interior portion of the grinding-member 40, where it engages the exterior por-

tion of the hollow bracket, is provided with a bushing 51 of Babbitt metal, or other suitable material, which may be readily renewed without the necessity for substituting 5 an entirely new grinding-member.

Located forward of the grinding-member 40 and coöperating with the latter, is a relatively stationary grinding-member 52, which is mounted in a housing 53 hinged as shown 10 at 54 to a stationary member 55 carried by a collar 56 surrounding the forward extremity of the hollow shaft. This housing is provided with an opening 57 through which the material to be ground may be 15 introduced to the space between the grinding jaws through an opening 58.

The forward extremity of the hollow shaft 6 is equipped with a collar 59 which is made fast thereto and provided with fan-blades 20 60 which are located within the housing and surrounding the hollow bracket 37, being arranged to rotate within the space of the housing into which the ground material which has been reduced by the grinding 25 members, must enter. This fan produces an air-current of sufficient strength to cause the properly ground material to be discharged from the housing through an opening 61 formed in an outlet 62 which may be in 30 communication with a receptacle of any desired character for the pulverized material.

In the rear of the housing and formed integral with the stationary collar 56, is a hollow drum 63 provided with perforations 35 64 communicating with the atmosphere. This drum also communicates with the interior of the housing in which the fan-blades 60 are located. Hence, as the fan is rotated within the housing, the suction produced 40 thereby will draw air thereinto through the perforations 64 of the hollow drum. The entrance of air through these perforations may be regulated at will by the adjustment of a band 65 which is rotatably mounted on 45 the drum and provided with perforations corresponding to those in the drum. It will thus be understood that this band may be adjusted by means of a suitable handle 66 so that its perforations may fully register 50 with the perforations 64 of the drum, or only partly register therewith as may be desired and according to the volume of air which may be required in order to produce the necessary current for removing the pulverized material from the housing.

The rear extremity of the operating shaft 55 bears against a steel disk 67 which is located within an opening 68 formed in the frame-work of the machine and interlocked 60 as shown at 69 with a non-rotatable block 70 which is longitudinally movable within the opening 68 of the casing, but prevented from rotary action by means of a key 71 secured to the block by a screw 72 and slidable in 65 a groove 73 formed in the casing outside of

the circumference of the opening 68. Located in the rear of the block 70 is a plunger 74 in which is threaded a screw 75 equipped at its rear extremity with a hand-wheel 76 exposed for manual operation. 70 This plunger 74 is recessed between its extremities as shown at 77 to receive toggle-links 78 which also engage recesses 79 formed in blocks 80 movable in hollow cylindrical members 81 formed on the rear extremity of the frame and being exteriorly open to receive interiorly-projecting tongues 82 formed on cross-heads 83 and 84 located respectively above and below the vertically-movable blocks 80. These tongues 82 are 80 centrally located on the cross-heads 83 and 84. The cross-head 83 is connected at its opposite extremities with rods 85 by means of nuts 86 threaded on the rods to engagement with the top of the cross-head. The 85 lower extremities of these rods are connected with a cross-head 87 whose opposite extremities are slidable on rods 88, there being a pair of rods 88 at each end of the cross-head 87. 90

Surrounding each rod 85 between a cross-head 89 and the cross-head 87, are a number of spiral springs 90, intermediate cross-heads 91 and 92 being employed in order to use a number of springs 90 instead of a single integral spiral spring extending between each pair of cross-heads 87 and 89, thus making it practicable to employ relatively stiff springs which are more easily manufactured than a single long spring of corresponding tension. 95

It will be understood that there is a pair of rods 88 arranged on each side of the hollow cylindrical members 81, the two rods 88 of each pair being located on opposite sides of the spiral springs 90 and the rods 85 which are surrounded by the said springs. The rods 88 of each pair are connected with one extremity of the cross-head 89 by means of nuts 93 which are applied to the rods 110 above the cross-head. The opposite extremities of these rods are connected with the cross-head 84 by means of nuts 94 located below the cross-head. All of the cross-heads 87, 91 and 92 are freely slidable on the 115 rods 88.

The upper extremities of both pairs of rods 88 extend beyond their nuts 93 as shown at 95 and pass through openings formed in the opposite extremities of the cross-head 83 whereby the cross-head is freely slidable on this rod extension. The object of the extensions 95 is to guide the cross-heads and maintain them at all times in the proper position, and to prevent any 120 tendency to get out of alinement with the other cross-heads of the construction. It will be observed that with the exception of the rod extensions 95, only two rods pass through the cross-heads 83, namely: the 125 130

rods 85, one passing through each extremity of the cross-head and in the center thereof, the said rods being connected with the cross-head as heretofore explained, by nuts 86.

5 From the foregoing description, it will be understood that whenever the grinding member 40 is thrust rearwardly from the co-operating grinding-member 52, whereby the operating shaft is thrust endwise in a 10 rearward direction, the blocks 80, through the instrumentality of the toggle-links 78, will be thrust outwardly from the plunger 74 and this action, through the medium of the tongues 82, will force the two cross-heads 83 and 84 outwardly, the one moving upward and the other downward, whereby the springs 90 are compressed. As soon, however, as the obstacle interposed between the grinding members has been removed, the 15 springs will restore the grinding-member 40 to its normal position with reference to the relatively stationary grinding-head 52.

As the lower cross-head 84 is moved downwardly by virtue of the operation hereinafter described, it acts upon a sort of bell-crank lever 96 which is connected by means of a rod 97 with a lever 98 to automatically shift the clutch 7 toward the left on the hollow shaft 6, a sufficient distance to release 20 the clutch from the operating pulley 8, whereby the power which operates the machine is disconnected from the shaft 6 and its associated elements, thus stopping the machine. The bell-crank lever 96 is fulcrumed as shown at 99 on a stationary part 25 100 of the frame-work. An arm 101 of this lever is acted on by the cross-head 84, while an arm 102 is connected as shown at 103 with one extremity of the rod 97, the opposite extremity of the last-named rod being 30 connected as shown at 104 with the lower extremity of the member 98, the latter being fulcrumed on the frame-work as shown at 105.

45 The upper arm of the lever 98 is forked, as shown at 106, to straddle the collar 9 of the clutch 7, the parts of this arm on opposite sides of the collar being pivotally connected as shown at 107 with a ring 108 loose 50 on the collar 9, and engaging a circumferential groove 109 formed in the collar. By virtue of this construction and arrangement, the clutch is slidably actuated on the hollow shaft 6 whenever the cross-head 84 55 is moved in either direction.

Referring again to the housing 53, the latter is pivotally connected as shown at 110 with a lever-arm 111 which is pivotally connected as shown at 54 with the bracket 55 heretofore described. Intermediate the extremities of the lever-arm 111 is a recess 112 in which is seated a spiral spring 113, the said spring also bearing on the upper portion 60 of the housing. The forward extremity of the lever-arm 111 is provided

with a face 114 which is adapted, when the housing is swung outwardly (see Fig. 8) to be engaged by a face 115 formed on a lug 116 of the housing.

The housing is locked in place by means 70 of a lever-like device 117 pivotally connected as shown at 118 with a stationary bracket 119 also connected with the collar 56 and the drum 63. This device 117 extends forwardly from the pivot 118, and with its 75 outer extremity is pivotally connected with a locking lever 120 fulcrumed on the device 117 as shown at 121. This locking lever is slightly angular in shape and is provided at one extremity with a hand-piece 122, its opposite arm 123 being equipped with a rounded bearing extremity 124 which is provided with a screw-stem 125 threaded into the arm 123, whereby the part 124 is adjustable. 85

The lower portion of the housing 53 is provided with a lug 126 which is provided with a curved recess 127 adapted to receive the extremity 124 of the lever 120, when the housing is in the closed position. In other 90 words, after the housing has been opened to the position shown in Fig. 8, in order to close it, it may be swung inwardly toward the rotary grinding-head to the dotted-line position in Fig. 8, after which, by the manipulation of the lever 120, the extremity 124 may be brought into engagement with the lug 126, and as the handle-extremity of the lever is swung in the direction indicated by the arrow in Fig. 8, the housing will be 95 thrown to its closed position, the device 117 being at the same time raised, and the lever 120 moved to a position in alignment with the device 117, thus locking the housing in the closed position. 100

105 From the foregoing description, the use and operation of my improved grinding mill will be readily understood. Power is delivered to the machine from a suitable source (not shown) through the medium of the 110 pulley 8, which, when the machine is in position for use, is engaged in operative relation by the clutch 7 splined on the hollow shaft 6, as heretofore explained. Hence, as 115 the pulley is rotated, the shaft 6 is also rotated, and motion is simultaneously imparted to the operating shaft 35 through the medium of the crank-arm 30, and the gears 32, 33 and 34. Hence, it will be understood that as the hollow shaft 6 is rotated, the 120 operating shaft 35 which is eccentrically mounted in the hollow shaft will have an orbital travel with the hollow shaft independently of its rotary motion on its own axis. Consequently, the grinding-member 125 40 is not only rotated for grinding purposes, but is also given in addition a lateral or sliding movement simultaneously, thus facilitating the performance of the grinding function. 130

The material to be treated is introduced through the opening 57 of the housing and passes thence through the opening 58 in the stationary jaw 52, into the space between the grinding jaws 40 and 52. As this material is ground to the necessary degree of fineness, it escapes from between the jaws into the interior of the housing 53 and is driven therefrom through the medium of a current 10 of air produced by the fan-blades 60 out of the housing through the opening 61, any particles which are too large to be removed by the air-current dropping into a slideable receptacle 128 which is supported by means 15 of a casing 129, connected with the lower part of the housing.

In the event that a substance too hard to be reduced by the grinding-members shall have been fed thereto, the rotary grinding member 40 will be thrust rearwardly, together with the operating shaft 35, and by virtue of the yielding capacity of the springs 90 arranged in connection with the cross-heads 83 and 84 heretofore described.

25 It must be understood that the grinding member 40 is permitted a slight rocking movement on the hollow bracket 37 with which it is connected. This is permitted by virtue of the curvature of the inner surface 30 of the member 40 where it engages a correspondingly curved surface 130 of the said bracket.

The coil spring 113 acts on the housing 53 in the rear of the center of the latter 35 and at a considerable distance from the pivot 110, whereby, as soon as the housing is unlocked by throwing the locking lever 120 to the unlocked position, the spring acting on the housing will automatically throw 40 the latter to the open position approximately as indicated by the dotted lines in Fig. 8.

As illustrated in the drawing, the stationary grinding-member 52 is secured to the housing by means of bolts 131.

45 In order to notify the person in charge of the machine that an article or foreign substance of such character has passed between the grinding members as to cause the operating shaft 35 to move rearwardly and actuate the clutch 7 to disengage the latter from the power-pulley through the instrumentality of the connections heretofore described, an electrical signal may be employed (see Fig. 1). This signal consists, as illustrated in the drawing, of a bell 132 connected by means 55 of a wire 133 with a pole 134 of a battery 135. The bell is also connected by means of a wire 136 with a contact 137 mounted on the frame but insulated therefrom, as 60 shown at 138. From the opposite pole 139 of the battery, a wire 140 leads to a contact 141 fast on the rod 97, but insulated therefrom as shown at 142. The two contacts 141 and 137 are located in such proximity to 65 each other that when the rod 97 is actuated

by the movement of the lever 96, in a direction to act upon the lever 98 to disengage the clutch from the power pulley, the contact 141 will be brought into engagement with its operating contact 137, thus closing 70 the battery circuit and operating the bell 132.

It will be understood that any suitable, electrically operated signal may be employed, whether audible, visual or both. 75

Attention is called to the fact that in my improved construction the grinding or pulverizing jaws are respectively convex and concave, there being special coaction between this construction of jaws and the construction whereby a gyratory movement is imparted to the movable jaw, this movement being a combination of the rotary movement imparted by the operating shaft 35, due to its movement on its own axis, and its movement with the hollow shaft due to its eccentric mounting therein, whereby it travels in an orbit simultaneously with its axial travel. 80

Having thus described my invention, what 85 I claim is:

1. In an ore grinder, the combination of a grinding-member, a rotary shaft connected in operative relation with said member, spring-actuated cross-heads movable at 90 right angles to said shaft, and an operative connection between the said shaft and said cross-heads whereby the springs act to impart an endwise thrust to the shaft in the direction of the grinding member. 95

2. In an ore grinder, the combination of a grinding-member, an endwise-movable rotary shaft connected in operative relation with said grinding member, coil springs having their axes at right angles to the axis 100 of the shaft, and an operative connection between said springs and the shaft to impart an endwise thrust to the latter. 105

3. In an ore grinder, the combination of a grinding-member, an endwise-movable rotary shaft connected in operative relation with said grinding-member, coil springs having their axes at right angles to the axis 110 of the shaft, and an operative connection between said springs and the shaft to impart an endwise thrust to the latter, comprising blocks acted on by the springs and movable at right angles to the axis of the shaft, and a toggle connection between the blocks and the shaft. 115

4. The combination of a grinding-member, a rotary endwise movable shaft connected in operative relation with the grinding-member, blocks movable at right angles to the axis of the shaft, cross-heads acting on the blocks, springs acting on the cross-heads, and a toggle connection between the blocks and the shaft to cause the tension of the springs to act on the shaft in an endwise direction. 120

5. In a grinder, the combination of an endwise-movable shaft, a grinding member connected in operative relation with one extremity of the shaft, blocks movable at right angles to the axis of the shaft, a toggle connection between the said blocks and the shaft, cross-heads acting on the blocks, springs acting on the cross-heads, a power pulley concentrically arranged with reference to the shaft but loose thereon, having a clutch splined on the shaft and connected in operative relation with the power pulley, and an operative connection between one of the said cross-heads and the clutch, whereby, as the cross-heads are thrust outwardly by the rearward movement of the shaft, the clutch is actuated to disengage the shaft from the power influence of the operating pulley, substantially as described.
- 10 6. In a grinder, the combination of an endwise-movable shaft, a grinding member connected in operative relation with one extremity of the shaft, blocks movable at right angles to the axis of the shaft, a toggle connection between the said blocks and the shaft, cross-heads acting on the blocks, springs acting on the cross-heads, a power pulley concentrically arranged with reference to the shaft but loose thereon, a clutch splined on the shaft and connected in operative relation with the power-pulley, and an operative connection between one of the said cross-heads and the clutch, whereby, as the cross-heads are thrust outwardly by the rearward movement of the shaft, the clutch is actuated to disengage the shaft from the operating pulley, said connection including a lever having one arm in engagement with the operating cross-head, a second lever having one arm in engagement with the clutch, and a rod connecting the two levers.
- 15 7. The combination of a grinding-member, a rotatable endwise-movable shaft having one extremity engaging a grinding-member, a hollow shaft in which the first named shaft is eccentrically mounted, an operating pulley loose on the hollow shaft, a clutch splined on the hollow shaft and connected in operative relation with the said pulley, a gearing connection between the hollow shaft and the first named shaft, and an operative connection between the first named shaft and the said clutch, whereby, as the first named shaft is thrust rearwardly, the clutch is actuated to disconnect it from the power-pulley for the purpose set forth.
- 20 8. The combination of a grinding-member, a rotary endwise-movable shaft having one extremity in engagement with the grinding-member, springs acting on the shaft to hold the latter in yieldable relation in an endwise direction with the grinding-member, means for applying rotary motion to the shaft, and an operative connection between said means and the shaft, whereby, as the latter is thrust rearwardly, the operating means is disconnected from the shaft, substantially as described.
- 25 9. In a grinder, the combination of a rotary grinding head, a shaft connected in operative relation with said head to rotate the same, a hollow shaft in which the first named shaft is eccentrically mounted, means for applying power to the hollow shaft, and to the first named shaft, a housing surrounding the grinding member, fan blades located in the housing and connected with the hollow shaft whereby the fan blades are rotated when the machine is in operation, a stationary drum in communication with the housing and having openings communicating with the atmosphere whereby, as the fan blades are rotated, a current of air is produced within the housing of sufficient strength to expel the pulverized material through an outlet with which the housing is provided.
- 30 10. In a grinder, the combination with an end-wise movable shaft, of a grinding member supported upon said shaft, blocks mounted for movement at right angles to said shaft, toggle connections between said blocks and shaft, springs tending to force the said blocks inwardly, a power pulley concentrically arranged with reference to the shaft but loose thereon having a clutch splined on the shaft and connected in operative relation with the power pulley, and an operative connection between one of said blocks and the clutch whereby as the blocks are thrust outwardly by the rearward movement of the shaft the clutch is actuated to disengage the shaft from the power influence of the pulley, substantially as described.
- 35 11. In an ore grinder, a shaft, a grinding member supported upon said shaft, means bearing upon said shaft tending normally to thrust it yieldably forward, a power pulley loosely mounted upon said shaft and a clutch acting normally to hold said shaft and pulley in operative position and means for automatically releasing said shaft under the influence of rearward pressure upon the same.
- 40 12. In a grinder, a casing, a grinding member in the casing, means for imparting a planetary movement to said member, a fan in said casing, means for rotating said fan about the center of revolution of said grinding member, said casing having a passage leading therefrom through which the ground material is adapted to be forced by said fan.
- 45 13. In combination, a shaft having a rounded end, a grinding disk having a socket adapted to fit said rounded end, a bracket slidably mounted on said shaft and adapted to engage said disk and a spring

tending to hold said bracket and disk in fixed relation.

14. In combination, a shaft having a rounded end, a grinding disk having a 5 socket adapted to fit said rounded end, a flange upon the rear of said disk, a bracket slidably mounted upon said shaft, a flange upon said bracket adapted to bear against the forward side of the flange upon the disk 10 and yieldable means acting upon said bracket tending to force said flanges together, whereby the bracket and disk are held in fixed relation.

15. In an ore grinder, a shaft, a grinding 15 member supported upon said shaft, means

bearing upon said shaft and tending normally to thrust it yieldably forward, a power pulley loosely mounted upon said shaft and a clutch acting normally to hold said shaft and pulley in operative relation, 20 and means for automatically releasing said shaft from the power pulley through the medium of the clutch, under the influence of rearward pressure upon the same.

In testimony whereof I affix my signature 25 in presence of two witnesses.

EDWARD F. McCOOL.
